(57) **CLAIM**

The ornamental design for garment closure system, as shown and described.

DESCRIPTION

FIG. 1 is a perspective view of the garment closure system, showing my new design;

FIG. 2 is a front view thereof,

FIG. 3 is a side view thereof; and,

FIG. 4 is another side view thereof, showing the design in an alternate position.

The broken line showing is for illustrative purposes only and forms no part of the claimed design.
